NEON SIGN

William G. Green, Tulsa, Okla.

Application November 11, 1935, Serial No. 49,211

6 Claims. (Cl. 40—130)

This invention relates to signs and more particularly to luminescent gas tube signs, the characters of which are illuminated to provide an advertising display.

5 The principal object of the present invention is to provide a sign of this nature in which the characters are removable in such a manner that advertising messages of variable context may be displayed.

10 Other objects of the present invention are to provide a so-called neon sign, the character and blank units of which may be mounted in any arrangement in parallel or series circuit and yet retain the resistance of the circuit at the rating 15 of the transformer supplying the sign; to provide differential resistances between the electrodes of individual characters whereby each character unit has equal resistance, and to provide novel means to adapt the sign for removing and replacing individual characters.

15 Other important objects of the invention are to provide an improved mounting of the gas tubes to expose only the portion of the tubes forming the characters, and to prevent entrance of moisture into the block units and between the blocks 20 and their support.

25 In accomplishing these and other objects of the invention I have provided improved details of structure, the preferred form of which is shown 30 in the accompanying drawings, wherein:

35 Fig. 1 is a perspective view of a theatre canopy equipped with "neon" tube characters embodying the features of my invention.

Fig. 2 is a perspective view of one of the characters, parts of the insulating mounting being broken away to show the tube electrodes, resistances and binding posts.

40 Fig. 3 is a perspective view of the rear portion of an individual character, particularly showing the plug connections for the characters with the base of the sign.

45 Fig. 4 is a longitudinal cross section on the line 4—4, Fig. 1, particularly showing the construction of the character mounting and block.

50 Fig. 5 is a vertical cross section on the line 5—5, Fig. 1, particularly showing the detail construction of one of the character blocks as it is mounted in the base.

55 Fig. 6 is a vertical cross section through one of the blank blocks of the sign particularly showing the resistance element used in the blank for establishing the same resistance value as the character blocks.

Fig. 7 is a rear elevational view, showing a

circuit whereby the blocks are connected in parallel.

Fig. 8 is a similar view, showing a circuit whereby the blocks are connected in series.

Referring more in detail to the drawings:

1 designates a sign embodying the features of the present invention which is mounted, for the purpose of illustration only, on the outwardly facing sides of a canopy 2 overhanging the entrance to a theatre or the like, the sign being 10 shown in this instance as including rows 3, 4, 5 and 6 made up of individual character bearing blocks 7 and blank blocks 8, which are so related as to present a message to the public.

15 The character bearing blocks 7, one of which is particularly shown in Fig. 2, each includes a rectangular base 9 of durable, rigid and insulating material such as hard rubber, one of the synthetic resins known as "bakelite", or other suitable material of similar nature. The base 9 includes side and end walls 10 and 11, a back wall 12, and an open front 13 to form a compartment 14 containing electrical parts of the blocks as now to be described.

20 The back wall 12 of the base is drilled centrally of its width and at spaced vertical points to provide apertures for the insertion of the threaded ends 15 of plugs 16 and 17. The plugs are provided at the inner termination of their threaded ends with circular flanges 18 for retaining cup shaped gaskets 19, and to provide stop shoulders for the threaded ends of the plugs. The other outer ends of the plugs are smoothly rounded and provided with peripheral grooves 25 spaced inwardly from said rounded ends for a purpose later described. The threaded ends of the plugs are provided with nuts 21 to hold the plugs firmly in the base and against which the terminal leads 22 from luminescent tubes 23 are retained by jamb nuts 24. The threaded ends of the plugs thus also serve as terminals 30 and 26 to facilitate connection of the tubes.

35 In order that the letters or characters may be interchangeable to compose any desired sign or wording it is necessary that each character have 40 the same resistance value, but since each character requires a different length tube to produce it, the resistances thereof vary and it is therefore necessary to connect thereto resistances having 45 the proper value to give each character the same electrical resistance so that when inserted in the sign they will be of the same brightness.

50 Therefore, resistances 27 and 28 of a strength predetermined in relation to the total length of 55

the tubes and electrical energy passing therethrough are connected in the leads 22.

The tubes 23 are formed of translucent material and are shaped to form the desired characters, after which they are filled with gases such as neon, helium or argon, under proper pressure conditions, and supplemented with suitable metallic vapors to emit desired colors when the gas is electrically excited, as in conventional practice.

A plastic insulating filler 29 is then suitably placed in the compartment 14 to enclose the binding posts and resistances and to cover the portions of the tubes not required in forming the characters. The character forming portions of the tubes are also partially embedded and cushioned in the filler 29 to protect them against breakage, and to prevent incorrect diffusion of light rays when the sign is illuminated. The plastic material also eliminates possibility of shorting of the high tension current across the terminals in damp weather.

It may be noted that in signs of this nature the source of energy for exciting the gas in the tubes is usually of a type which must be stepped up to provide high potential energy to obtain the best result for illumination of the gas in the tubes. In accomplishing this stepping up, a transformer 31 of conventional design is positioned between the source of current and the circuit wires 32 leading to the buss connections for the characters.

The blank blocks 8 include bases and terminal plugs of identically the same construction as the character blocks; the terminals, however, are connected by a resistance 33 of the same value as the letter blocks. The resistance 33 is completely embedded in the plastic filler so that the front faces of the blocks present flat surfaces in plane with the front faces of the letter or character blocks.

The blocks, both character and blanks, are mounted in any desired sequence on a sign board 35 to present an advertising message to the public. The sign board 35 is provided with a series of openings 36 arranged in rows 37 conforming in spacing to the spacing of the plug terminals of the respective blocks. The outer ends of the apertures 36 are enlarged as at 37, to provide clearance for the bearing portions 18 of the plugs, and to provide a close fit for the block against the base whereby danger of "shorting out" the lights due to water collecting around the plugs between the blocks and base is prevented, the cup-shaped gaskets 19 being compressed for aiding in preventing such "shorting out".

When the plugs are inserted through the openings, the rounded ends thereof complete a circuit through plug retaining contacts 38 and 39, plan views of which are shown in Figs. 7 and 8, and cross sections thereof in Figs. 5 and 6. The brackets are suitably secured to the rear side of the sign base mounting as by the screws shown. The contacts include spring fingers 40 having in-struck ribs 41 for engaging in the grooves 20 of the plugs to hold them in position on the sign until forcibly removed therefrom. One of the retaining screws on each bracket is provided with a binding post 42 for securing a wire 43 leading to and from a source of current in connection with all of the blocks in one circuit.

The blocks as described, may be connected in either parallel or series circuits.

In Fig. 7 I have shown the sign blocks mounted in a sign in which the contacts are wired in a

parallel circuit, the characters being connected across the conductors 44 and 45 leading from the terminals of the transformer 31. If the sign is of large size, a selective number of contacts may be connected in one circuit and the remainder in another circuit. However, in any instance, each circuit in the sign will always have the same current demand regardless of the word characters used in composing the sign.

In Fig. 8 I have shown the contacts of the sign 10 as connected in series circuit by means of conductors 46 connecting the contact of one block with the opposite contact of an adjacent block, as shown.

In assembling a sign constructed as described, 15 various individual blocks, selected to spell out desired words are mounted on the sign base by inserting the plugs on the blocks through the apertures in the base, so that they engage the contacts on the rear side of the sign board as 20 shown in Fig. 5. The spaces between the words are filled in by blank blocks having the resistances 33. If all of the plug-in places in the circuit are not filled when the sign is completed, 25 blank blocks are applied to these spaces to maintain the resistance of the circuit at a constant value and within the range of the transformer.

When the blocks are assembled, current courses through the wires 43, contacts 38-39, plugs 16-17, resistances 27-28, and the gas 30 filled tubes of each letter block to excite the gas and illuminate that portion of the sign, after which the current flows through the outlet current wire, completing the circuit.

From the foregoing it is apparent that I have 35 provided a sign of the luminescent gas filled type wherein the individual units are readily removable to change the wording or character of the sign for any desired occasion. It is also apparent that the current demand for any set up of 40 letters is kept at a constant value and within the range of the transformer.

What I claim and desire to secure by Letters Patent is:

1. In a sign of the character described, a sign 45 character including a block of insulating material having an open front compartment, contact plugs carried by said block, a gas charged tube carried in the block and having electrical connections with the plugs, a resistance element in 50 the block and connected in series with one of the plugs and with the tube, and a plastic insulating material filling said compartment to enclose the resistance element and to expose selective portions of the tube to form a character.

2. In combination with a sign character mounting member having a plurality of pairs of openings arranged in definite relation to each other and electrical contacts carried by the mounting member in registering alignment with 60 said openings, a plurality of characters each including a block of insulating material, plugs carried by said blocks and projectable through any selected pair of openings for engaging said contacts, gas charged tubes carried by the blocks, 65 and electrical connections between the tubes and the plugs including compensating means whereby the characters are interchangeable with each other to compose a sign.

3. In combination with a sign character 70 mounting member having a plurality of pairs of contacts and means supplying electric current to the contacts a plurality of sign characters each including a block, means carried by each block for engaging any one of the pairs of contacts, 75

- gas charged tubes carried by selected blocks, electrical connections between the tubes and the contacting means of the selected blocks, electrical resistance elements connected in circuit with the contact means of the other blocks, and compensating resistances connected with the tubes whereby the blocks having the tubes have substantially the same electrical resistance as the blocks provided with the electrical resistance elements.
4. In combination with a sign character mounting member having a plurality of pairs of openings arranged in definite relation to each other and electrical contacts carried by the mounting member in registering alignment with said openings, a plurality of characters each including a block of insulating material having an open front compartment, plugs carried by each block projectable through any selected pair of openings for engaging said contacts, gas charged tubes carried by selected blocks, and resistances in other blocks connected with the plugs of said other blocks having substantially the same electrical resistance values as the gas charged tubes whereby the blocks are interchangeable with each other.
5. In combination with a sign character mounting member having a plurality of pairs of openings arranged in definite relation to each other and electrical contacts carried by the mounting member in registering alignment with said openings, a plurality of sign characters each including a block of insulating material having
- an open front compartment, plugs carried by said block projectable through any selected pair of openings for engaging said contacts, a gas charged tube carried in the block and having electrical connections with the plugs, a plastic insulating material filling said compartment and exposing selective portions of the tube to form a character, and compensating means for each of said sign characters whereby all of said characters have substantially the same electrical resistance and are interchangeable one with the other.
6. In combination with a sign character mounting member having a plurality of pairs of openings arranged in definite relation to each other and electrical contacts carried by the mounting member in registering alignment with said openings, a plurality of sign characters, blocks of insulating material having an open front compartment, plugs carried by said blocks and projectable through any selected pair of openings for engaging said contacts, a gas charged tube carried in certain of the blocks and having electrical connections with the plugs, a plastic insulating material filling said compartment and exposing selective portions of the tube to form a character, resistance elements in the compartment of the other blocks and connected with the plugs of said blocks, and compensating means for each of said tubes whereby all of said characters have substantially the same electrical resistance as said resistance elements and are interchangeable one with the other.

WILLIAM G. GREEN.
